UNITED STATES PATENT OFFICE

THOMAS F. NOONAN, OF CHICAGO, ILLINOIS, ASSIGNOR TO FRED H. RIX, OF CHICAGO, ILLINOIS

LOCK

Application filed April 7, 1932. Serial No. 603,845.

The invention relates to locks, and has for its object to provide a lock particularly adapted for use in connection with gas meter cocks, but applicable for general use and comprising a body having an axially movable sliding bolt therein held in locked position by spring detent members cooperating with channels in the bolt, and means whereby a key may be inserted axially into the inner end of the bolt between the detent members for forcing the detent members into disengaged relation to the bolt.

A further object is to provide the lower end of the lock body with a key receiving aperture in registration with the slot in the bolt and to provide a member carried by the lock body and extending through the slot for guiding said bolt axially in its movement in either direction in registration with the key receiving slot.

A further object is to taper the inner end of the bolt so that when the bolt is forced between the detents, the detents will spread and spring into the channels in the bolt when the bolt is in inner position.

A further object is to provide the axially movable bolt with tapered portions adjacent the shoulders and forming means whereby the spring actuated detents are forced outwardly when the bolt is forced inwardly so that the detents will be received in the annular channels of the bolt.

A further object is to slidably mount the spring actuated members in chambers at opposite sides of the bolt and in the plane of the slot in the bolt whereby a key forced axially into the bolt slot will spread the spring actuated members apart and allow axial movement of the bolt from the lock body and key.

A further object is to provide the bolt with a head adapted to engage the upper side of the valve arm and pass downwardly through an aperture in an arm carried by the valve casing for locking said valve and casing against rotation in relation to each other.

With the above and other objects in view the invention resides in the combination and arrangement of parts as hereinafter set forth,

shown in the drawing, described and claimed, it being understood that changes in the precise embodiment of the invention may be made within the scope of what is claimed without departing from the spirit of the invention.

In the drawing:

Figure 1 is a perspective view of a conventional form of plug valve, showing the device applied thereto.

Figure 2 is an end view of the valve.

Figure 3 is a vertical longitudinal sectional view through the lock, showing the spring actuated detents in open position and the key in the lock.

Figure 4 is a vertical longitudinal sectional view through the lock, showing the same in locked position.

Figure 5 is a vertical transverse sectional view through the lock.

Referring to the drawing, the numeral 1 designates the body of the lock, in the bore 2 of which the lock bolt 3 is slidably mounted for axial movement only. Bolt 3 is provided with a slot 4 extending inwardly from the tapered lower end 5 thereof and extending transversely through said slot and the body 1 of the lock is a guide pin 6, which guides the bolt during its axial movement, and holds the same in a position where the lower end 80 of the slot 4 will register with the key aperture 7 in the lower end of the body 1, so that the key 8 will be received axially in the bolt and slot for the unlocking operation.

Bolt 3 is provided with annular channels 9 which form shoulders 10, over which the spring actuated detents 11 spring into the channels for positively locking the bolt against axial removal from the lock body 1. Detents 11 are preferably provided with heads 12, disposed in chambers 13 in opposite sides of the lock body, and interposed between said heads and plugs 14, abutting the outer ends of the chambers 13, are expansion springs 15, which normally force the detents 11 inwardly into the path of the tapered end 5 of the bolt and the tapered portion 16 of the bolt. Plugs 14 may be welded or otherwise anchored in the chambers so as to conceal the positions.

Although two pairs of detents 11 are shown, it is to be understood the number may be varied according to the size of lock desired. It is obvious in small devices a single pair would be sufficient. The device is particularly adapted for use in connection with gas cocks, however it will be understood that it is applicable to general use. In Figures 1 and 2, the device is shown on a gas cock, which 10 comprises a valve casing 17 having a rotary plug valve 18 therein. The rotary plug valve 18 is provided with an arm 19, which registers with the arm 20 carried by the valve casing 17, said arms are provided with registering apertures 21, through which the bolt 1 extends. After the bolt 1 is passed through the apertures 21, the tapered end 5 thereof is placed in the bore 2 of the lock body 1, and the body is rotated until the pin 6 is received in the slot 4 of the bolt; then the body 1 is forced upwardly towards the head 22 of the bolt and the tapered end 5 is forced between the detents 11, springing the same outwardly against the action of the expansion 20 springs 15, until the detents are received in the channels 9 of the bolt above the shoulders 25. It will be noted that the key is received axially into the end of the bolt, and the slot 10 registers with the key slot 7 in the lock body 30 at all times incident to its slidable mounting on the pin 6.

From the above it will be seen that a lock is provided which is particularly adapted for use in connection with cocks, for instance of 35 the meter type, and that the bolt receives the key actually therein. It will also be seen that the device is simple in construction, positive in its operation, and constructed in a manner whereby it may be cheaply manufactured and 40 sold.

The invention having been set forth what is claimed as new and useful is:—

1. A lock comprising a body, a bolt slidably mounted in said body for axial movement, a guide pin carried by the body and extending through a slot in one end of the bolt, said guide pin forming means for maintaining the slot in registration with a key receiving aperture in the body, spring actuated detent means carried by the body and cooperating with the bolt for holding the same within the body, said detent means being in the plane of the slot and positioned whereby when a key is forced axially into the slot of the bolt 45 it will be engaged by the key and disengaged by said key from the bolt.

2. The combination with a lock body, a bolt slidably mounted in said body and having a slotted end, annular channels carried 60 by said bolt, spring actuated detents cooperating with the bolt in the plane of the slot and received within the channels, of means whereby a key may be inserted through the lock body axially into the bolt slot in the path of 65 the detent means.

3. The combination with a lock body, a bolt slidably mounted in said body, one end of said bolt within the body being slotted, guide means carried by the body and extending into the slot of the bolt for guiding the same in its axial movement and preventing rotation of the bolt, one end of the body having a key receiving aperture in alignment with the slot of the bolt, spring actuated detents carried by the body and extending into the bore thereof, tapered shouldered members carried by the bolt in the path of the detent members, said detent members being in the plane of the slot whereby when a key is inserted axially into the bolt said detent members will be forced out of the bore. 70 75 80

4. A lock comprising a body having a bore therein, a non-rotatable axially movable bolt mounted in said bore, the portion of the bolt within the body being slotted, a key receiving aperture in the body in the plane of the bolt slot, spaced tapered shouldered members carried by the bolt, spring actuated detents carried by the body in the path of the tapered shouldered members and in the plane of the slot. 85 90 95

5. A lock comprising a body member, a slotted bolt slidably mounted in the body member, spaced tapered shoulders carried by the slotted end of the bolt, a key receiving aperture in the body member in the plane of the slot of the bolt and forming means whereby a key may be inserted axially into the slot of the bolt and between the detent means. 100 105

6. A lock comprising a body member, a slotted bolt slidably and non-rotatably mounted in the body member, spaced shoulders carried by the bolt thereby forming channels, spring detent members carried by the bolt member in the plane of the slot of the bolt and adapted to be received in the channels and a key receiving aperture carried by the body member in the plane of the bolt slot and adapted to receive a key. 110 115 120

7. In combination a lock body, a bolt axially movable in a bore in the body, detents cooperating with said bolt for holding the same within the body, a convoluted key way in the body axially disposed in relation to the bolt, said bolt having its end adjacent the keyway longitudinally slotted in registration with the convoluted keyway and adapted to axially receive a convoluted key when inserted through the convoluted keyway. 115 120

8. A device as set forth in claim 7, including a guide pin extending through the slot in the bolt and forming means whereby said bolt slot is maintained in alignment with the convoluted keyway. 125

In testimony whereof he hereunto affixes his signature.

THOMAS F. NOONAN.
